SEWING MACHINE

Otto R. Haas, North Beverly, Mass., assignor to
 United Shoe Machinery Corporation, Paterson,
 N. J., a corporation of New Jersey

Original application April 21, 1933, Serial No.
 667,224. Divided and this application Septem-
 ber 28, 1935, Serial No. 42,665

9 Claims. (Cl. 112—57)

The present invention relates to sewing machines, and is herein set forth as embodied in a lockstitch outsole shoe stitcher of the type described in the present inventor's pending applications for U. S. patent Ser. No. 600,016, filed March 19, 1932, and Ser. No. 667,224 filed April 21, 1933, the present application being a division of the latter.

The object of the invention is generally to improve the construction and mode of operation of the stitch-forming devices of a sewing machine and particularly to provide a lockstitch outsole shoe sewing machine of the type mentioned which is more efficient, reliable and uniform in operation as compared to prior sewing machines.

In the machine of the inventor's prior application, Ser. No. 600,016, a stopping mechanism is provided to stop the machine with the needle and awl disengaged from the work, and with the take-up moved from a maximum thread retracting position to a position where a part of the needle thread is yielded up as the machine comes to rest. In that machine the slack thread yielded up by the take-up during the final movements of the machine is likely to be withdrawn from the work support as the work is being removed, so that upon starting the machine on a new shoe, the end of the needle thread extends from the first stitch so far as to require hand trimming with resulting waste of thread.

According to a feature of the present invention, means is provided in a sewing machine arranged to operate in the manner just described, for preventing the thread from being withdrawn after the machine is brought to rest. In the present form of the machine, an additional movement is imparted to the take-up by connections to the stopping mechanism, so that substantially no slack thread is provided when the stopping mechanism has operated, and a complete seam will be formed which requires no hand trimming operation.

This and other features of the invention including certain novel and improved thread break indicating devices and novel and improved constructions and arrangements of parts are herein described in the following detailed specification, and are more particularly pointed out in the appended claims.

In the drawings, Fig. 1 is a view in front elevation of the sewing mechanism of a machine embodying the present invention with certain parts broken away or removed; Fig. 2 is a plan view partially in section and broken away on a re-

duced scale showing a part of the driving mechanism for the machine; Fig. 3 is a sectional view of the sewing mechanism taken along the line 3—3 of Fig. 1; Fig. 4 is a sectional view taken along the line 4—4 of Fig. 1, of a portion of the mechanism shown in Fig. 3, indicating the thread cutter in cutting position; Fig. 5 is a view in side elevation on a slightly enlarged scale and partly in section of the mechanism shown in Fig. 3, looking from the opposite side of the machine; Fig. 6 is a plan view partly in section along the line 6—6 of Fig. 5 showing a part of the take-up actuating mechanism; Fig. 7 is a sectional view in elevation of some of the take-up parts shown in Fig. 6; Fig. 8 is a side view partly in section taken along the line 8—8 of Fig. 7, showing more particularly the relations of the parts upon the occurrence of slack or broken thread; and Fig. 9 is a view similar to Fig. 8 showing the position of the parts during sewing.

Referring to the drawings, the frame of the machine comprises a main base 2, (see Figs. 1 and 2) a frame 4 containing the power driving mechanism and supporting a motor, and a frame 6 supporting the sewing mechanism. The motor drives the machine through a vertical shaft 8 arranged to rotate continuously while the motor is running. The mechanism in the base 2 and the sewing mechanism are driven by suitable gearing mounted within the frames from the continuously rotating shaft 8 through a clutch comprising a driving member 10 (see Fig. 3) and a driven member 12.

The sewing mechanism of the machine, as illustrated, is arranged to stitch the outsole to a lasted shoe, the shoe being operated upon being indicated at 14 in Fig. 4 of the drawings.

The sewing mechanism is operated from a sewing cam shaft 16 rotated from the driven clutch member 12 through a pair of helical gears 18 and 20 attached to the clutch member and to the cam shaft, respectively. When it is desired to stop the machine, the driven clutch member 12 is disengaged from the driving clutch member 10 by a driving and stopping mechanism comprising in part a bell-crank 22 secured to a shaft 24 in the frame 4, and rocked in a counter clockwise direction, as viewed in Fig. 3 through the engagement of a bolt 26 on one arm of the bell-crank with a cam slot 28 in a sleeve attached to the driven clutch member 12. The return movement of the shaft 24 and the bell-crank 22 in a clockwise direction is prevented by a latch 30 which engages the vertical arm of the bell-crank and causes the clutch to be disengaged by the 55

action of the cam slot 28 on the bolt 26 in the horizontal arm of the bell-crank 22.

The thread is severed at the end of a seam by a thread cutter indicated at 32, of the same construction and mode of operation as that described in inventor's co-pending application for Shoe sewing machine, Serial No. 651,803, filed January 14, 1933, in which a knife is projected against and enters beneath the surface of the shoe sole while 10 the shoe is held in operative position, so as to sever the threads with the ends remaining in engagement with the work, as shown in Fig. 4.

After the operations on the shoe are completed 15 having been substituted for the one on which the operation is complete, the machine is again started by engaging the driven clutch member 12 with the driving clutch member 10. To cause the movement of the driven clutch member against 20 the driving clutch member, a power driven shaft 34 (Fig. 2) having a crank portion 36 connected by a pitman and other suitable means to release the bell-crank 22 from the latch 30 is caused to rotate through one complete revolution by the 25 manipulation of a starting handle 38.

The stitch forming and work feeding devices of the machine include a curved hook needle 40, a curved awl 42, a looper 44, a shuttle or loop taker 46, a main take-up 48, an auxiliary take-up 30 50, a thread finger 52, a needle guide 54, a work support 56, a presser foot 58, and a feed slide 60 on which certain of the stitch forming devices are carried. The stitch forming and work feeding devices operate with a continuous feeding 35 movement to form a lockstitch seam, and at the end of the operation, the stopping mechanism including the bolt 26 on the bell-crank 22 and the cam slot 28 in the driven clutch member 12 are arranged to bring the sewing mechanism to 40 rest at a definite point with the needle and awl 45 disengaged from the work. To permit the stitch-forming devices to operate at high speeds, the timing is so arranged that the awl enters the work after the needle has withdrawn with its loop 50 of thread and while the needle thread is being interlocked with the locking thread by the shuttle. With this system of timing, it is necessary to cause the looper to misloop the needle in bringing the machine to rest after the last needle loop 55 has been drawn down into the work in order that the machine may stop with the needle free of thread and at a point in the cycle of operations in which, when the machine is again started, the awl will enter the work before the needle.

55 The take-up operates to draw the needle loop with the locking thread towards the work, and to set the stitch during the final thread retracting movement of the take-up. The position of the lock between the threads in the work is determined by the amount of thread withdrawn 60 from the shuttle. All of the operations and mechanism thus referred to are substantially the same, except as hereinafter described, as in the machine of the inventor's applications Ser. Nos. 65 600,016 and 651,803.

65 At the end of the sewing operation after the thread cutter 32 has acted and the shoe is being moved away from the work support, the frictional engagement of the ends of the threads and particularly the end of the needle thread, indicated at 62, (Fig. 3) in the work tends to cause the threads to be drawn with the shoe. The action of the needle thread tension, indicated at 64 is sufficient to prevent drawing an unlimited amount 70 of thread from the needle thread supply. How- 75

ever, with the use of the timing referred to, and the present stopping mechanism, the main take-up is actuated during the final movements of the machine to give up a certain portion of the thread. Due to the failure of the looper to loop 5 the needle on the last cycle of the machine, a supply corresponding to the thread releasing movement of the take-up may be withdrawn from the work support with the shoe after severing the threads. As the machine is started on a new 10 shoe, the amount of thread attached to the first stitch, unless otherwise taken up, may be so long as to require trimming after the shoe is removed from the machine.

In order to prevent a substantial length of 15 needle thread from being withdrawn from the work support at the end of a seam by frictional engagement with the shoe sole, an extra movement, according to the present invention, as will be hereinafter more fully described, is imparted 20 to the take-up during the final movements of the machine so as to bring it into a position substantially the same as its position during sewing in which the maximum amount of thread is retracted. This position may be suitably regulated 25 to cause the exact amount of thread required for the initial stitch in a new seam to be retained on the work support after the shoe is removed.

The means for actuating the take-up 48 during 30 sewing comprises a cam actuated lever 66, fulcrumed on a shaft 68 provided with a gear segment 70 on one arm cooperating with a segment 72 fixed to a shaft 14 on which the take-up is secured. The shaft 14 is rotatably mounted in a 35 sleeve 76 (see Fig. 6) arranged to slide along an arcuate slot 78 in the frame of the machine. The sleeve 76 is retained within the slot by a curved cover plate 80 secured at its ends to the portion of the frame in which the slot is formed. 40 The surfaces of the slot are arranged concentrically with the shaft 68 about which the segment 70 is oscillated, so that movement of the sleeve 76 supporting the shaft 14 will not cause the segment 72 to be disengaged from the segment 70. During the sewing operation of the machine the sleeve 76 is retained at the upper end of the slot 78 and the take-up 48 is oscillated by the shaft 14 in the usual manner. At the end of the sewing operation, a set of connections 45 actuated from the stopping mechanism is operated to move the sleeve 76 towards the lower end of the slot 78 causing the segment 72 to oscillate the take-up 48 to a position substantially 50 corresponding to the extreme thread retracting 55 position of the take-up during sewing.

The connections to the stopping mechanism for causing the take-up to be retained in its maximum thread retracting position, as the machine is stopped, comprises the shaft 24 of the stopping 60 mechanism, a block 82 (see Figs. 1, 2, 3 and 6) mounted on the end of the shaft, a block 84 mounted on a shaft 86 and coupled to the block 82 by a tongue and groove connection, a gear segment 88 (see Fig. 2) fixed to the other end of the shaft 86 65 and a segment 90 on one arm of a U-shaped lever 92 fulcrumed loosely on a horizontal shaft 94 at the back of the machine. The U-shaped lever 92 is connected with a sleeve 96 surrounding the shaft 94 and carrying an arm 98 secured thereto by means of a clamp bolt 100. The arm 98 carries a pivot block 102 slidably arranged on the upper end of a rod 104 pivotally connected at its lower end to a pivot 106 of a toggle connected for operating the sleeve 76.

The sleeve 76 is secured at its ends to a pair of links 108 and 110 (see Fig. 6), the link 108 being loosely mounted on the shaft 68 for the take-up actuating lever 66 and the link 110 being mounted upon a threaded stud 112 supported by a lug on the frame of the machine. The links 108 and 110 are connected together between their ends by a shaft 114 to cause them to move together, and their position is controlled by the movement of the toggle comprising a link 116 and a lever 118. The lever 118 is mounted on a shaft 119 in the frame and is pivotally connected with the link 116 by the pivot 106 which passes through the lower end of the link 104. When the rod 104 is moved upwardly by the engagement of the block 102 with a nut 120 on the rod 104 through the action of the connection to shaft 24 of the stopping mechanism in bringing the machine to rest, the alinement of the toggle links is broken (see Fig. 4) causing the take-up to move to its lowest position. The connections are maintained in this position by a compression spring 121 acting between one arm of the lever 118 and a pivot 122 rotatably mounted in a portion of the frame 6 to provide a snap action to the toggle movements. The spring 121 surrounds a rod 124 secured at one end to the pivot 122 and slidingly arranged in a transverse opening through a pivot 126 mounted in a downwardly curved arm of the lever 118 against which the spring 121 bears. The toggle is maintained in a definite broken position by contact of one arm of the toggle lever 118 with an adjustable set screw 127 threaded into a lug extending from the link 116. The final stopping position of the take-up and therefore the amount of thread to be employed in forming the first stitch on a new seam may be regulated by adjusting the set screw 127.

When the machine is started, the starting handle 38 being actuated to cause the crank shaft 34 to rotate, the sleeve 76 for supporting the take-up shaft 74 is moved to the upper end of the slot 78. The connections for so moving the sleeve 76 comprise an eccentric 128 on one end of the shaft 34, an eccentric strap 130 surrounding the eccentric, a link 132 connected between the eccentric strap and an arm 134 fixed to one end of the shaft 94 on which the lever 92 is mounted. Rotation of the crank shaft 34 in starting the machine causes shaft 94 to be rocked first in one direction and then the other and an arm 136 secured to the shaft is caused to engage the upper end of the rod 104, forcing the rod downwardly to move the toggle comprising the link 116 and the lever 118 into alinement. This movement causes the sleeve 76 to be shifted to the upper end of the slot 78 and to be held in this position by the snap action of the spring 121 while the machine is in operation.

In the machine described, some of the connections which operate simultaneously to move the sleeve 76 carrying the take-up shaft are also employed to cause the looper to misloop the needle after the last formed stitch. These connections operate in the same way as described in the machine of the inventor's applications, above identified, and are arranged to be operated from an arm 138 extending from the U-shaped portion of the lever 92. The arm 138 carries a perforated block 140 in which the upper end of a link 142 slides and movement is imparted to the link from the block by the engagement of the block with an adjusting nut 144 carried by the upper end of the link. Upward movement of the link 142 causes the path of movement of the looper to be shifted

away from the path of the needle. The looper actuating connections are returned to normal sewing positions by downward movement of the link 142. The link 142 is moved downwardly by an arm 146 fixed to the shaft 94 between the arms of the U-shaped lever 92 and is rocked simultaneously with the movement of the arm 136 which returns the take-up to normal operating position.

To indicate by stopping the machine or otherwise, breakage of the needle thread as in the machine of the co-pending applications, an electrical switch is arranged to be operated jointly by the main and auxiliary take-ups. Due to the movements of the pivot shaft 74 of the main take-up on the machine frame, the switch and auxiliary take-ups are separately mounted and additional connections are provided for operating the switch from the main take-up.

The thread break indicating switch shown in Figs. 6 to 9, comprises a pair of rotatably movable segmental contact disks 148 supported between insulating washers 150 carried by a sleeve 152 and a movable contact 154 mounted on the auxiliary take-up 50. The movable flat spring contact 154 when brought into engagement with the disks 148 causes the current to flow therebetween, and the disks 148 are connected by a pair of sliding contacts 156 with conductors 158 leading to a suitable electro-magnetic device for actuating the stopping mechanism of the machine. The sleeve 30 152 carrying the contact disks 148 is rotatably mounted upon a shaft 160 mounted at one end in a slot in a plate 162 secured to the machine and the auxiliary take-up is rotatably mounted at the other end of the shaft. The auxiliary take-up 35 exerts a yielding tension on the thread and a spring 164 is connected from an arm of the take-up with the frame of the machine for this purpose. When the thread is broken or the tension released, the auxiliary take-up will move the contact 154 towards the vertical portions of the contact disks 148, but will not cause engagement therewith unless the main take-up is in its extreme thread retracting position. The contact disks are held in a position out of engagement with the contact 154 by a spring 166 connected between an arm 168 extending from the sleeve 152 and the machine frame. The spring 166 acts to hold the arm 168 in engagement with a shoulder 170 on the frame and a portion of the arm extends 50 into the path of movement of the main take-up 48 so that the main take-up will engage the arm 168 only in the maximum thread retracting position of the take-up.

When the take-up engages the arm 168 the contact disks are moved into a position in which the contact 154 may engage them. As the take-up moves to release the thread the arm 168 again engages the shoulder 170 causing the arm to remain at rest during the remainder of the machine 60 cycle. With this construction the movement of the take-up pivot 74 at the end of the seam does not interfere with the operation of the thread break indicating switch.

The nature and scope of the invention having 65 been indicated and a specific embodiment illustrating the several features of the invention having been described, what is claimed is:

1. A sewing machine having, in combination, a work support, a presser foot, a needle, a take-up 70 movable during sewing to take up and give up thread as the thread is passed through the work, and means acting to prevent the thread normally given up by the take-up during sewing from being withdrawn with the work as the work is 75

- removed from the work support after the machine comes to rest.
2. A sewing machine having, in combination, a work support, a presser foot, a needle, a take-up, means for actuating the take-up during sewing to take up and give up thread as the thread is passed through the work, and means for causing the take-up to be moved as the machine is brought to rest to a position in which the amount of thread taken up is substantially the same as at the limit of the retracting movement of the take-up during sewing.
3. A sewing machine having, in combination, a work support, a presser foot, a needle, a take-up, a shiftable pivot on the machine for the take-up, means for oscillating the take-up about its pivot during sewing to take up and give up thread as the thread is passed through the work, and means for shifting the take-up pivot as the machine is brought to rest to prevent the thread normally given up by the take-up during sewing from being withdrawn from the work support.
4. A sewing machine having, in combination, a frame, a needle, a main take-up, a shiftable pivot on the frame for the main take-up, means for oscillating the take-up about its pivot during sewing to take up and give up thread as the thread passes through the work, means for shifting the pivot for the main take-up at the end of the sewing operation, an auxiliary take-up, a shaft on which the auxiliary take-up is mounted, a thread break indicating device, operated in part by the auxiliary take-up and an arm connected to said thread break indicating device and arranged to contact with the main take-up to cause the indicating device to be operated by the joint action of both take-ups.
5. A sewing machine having, in combination, a needle, a main take-up, a pivot for the main take-up, means for oscillating the main take-up about its pivot during sewing to take up and give up thread as the thread passes through the work, an auxiliary take-up, a movable switch contact connected for movement with the auxiliary take-up, a second contact yieldingly retained in a position where it will not engage the first contact but movable into engagement with said first mentioned contact for indicating a thread break, and an arm mounted in a position to be operated by the main take-up towards a position in which said contacts may be engaged during a part of the movement of the main take-up and arranged to be held stationary in a position in which the contacts can not come into engagements during the remainder of the main take-up stroke.
6. A lockstitch shoe sewing machine having, in combination, a work support, a presser-foot, a needle, a take-up, a pivot for the take-up, a shiftable block on which the take-up pivot is mounted, means for oscillating the take-up about its pivot comprising a driving segment and gear teeth connected to the take-up to take up and give up thread as the thread is passed through the work, and means for shifting the block relatively to the driving segment to prevent the take-up from giving up thread as the machine is brought to rest.
7. A sewing machine having, in combination, a work support, a hook needle, a needle looper, a take-up movable during sewing to take up and give up thread as the thread is passed through the work, and means acting when the machine is brought to rest to increase the amount of thread taken up by the take-up and when the machine is started to release the additional amount of thread taken up.
8. A sewing machine having, in combination, a work support, a presser foot, a needle, a take-up movable during sewing to take up and give up thread as the thread is passed through the work, mechanism for starting the machine in operation, mechanism for stopping the machine, and connections actuated by the stopping mechanism to prevent the thread normally given up by the take-up during sewing from being withdrawn from the work support with the work as the work is removed from the work support after the machine comes to rest, and connections actuated by the starting mechanism to release the thread for continued operation of the machine.
9. A lockstitch shoe sewing machine having, in combination, a work support, a presser foot, a needle, a take-up, a pivot for the take-up, means for oscillating the take-up about its pivot comprising a driving segment and gear teeth connected to the take-up to take up and give up thread as the thread is passed through the work, a shaft on which the driving segment is mounted, an arm rotatable about the shaft for supporting the take-up pivot, and means for shifting the arm relatively to the driving segment to prevent the take-up from giving up thread as the machine is brought to rest.

OTTO R. HAAS.
